UNITED STATES PATENT OFFICE.

OTTO M. SUMMERS, OF DAYTON, OHIO, ASSIGNOR, BY MESNE ASSIGNMENTS, TO
FRIGIDAIRE CORPORATION, A CORPORATION OF DELAWARE.

REFRIGERATING APPARATUS.

Application filed October 31, 1927. Serial No. 222,901.

This invention relates to refrigerating apparatus particularly to the form of refrigerating element and its arrangement in household refrigerator cabinets.

5 One of the objects of the invention is to provide an improved and simplified form of evaporator which is effective to cool circulating air in a cabinet and to freeze ice for table use, and which may be placed within a confined space.

10 Another object of the invention is to improve and simplify the arrangement and construction of evaporators to reduce their cost of manufacture.

15 Further objects and advantages of the present invention will be apparent from the following description, reference being had to the accompanying drawing, wherein a preferred form of the present invention is clearly shown.

20 In the drawings—

Fig. 1 is a front elevation of a refrigerator cabinet having the improved refrigerating element therein;

25 Fig. 2 is a vertical section through the cabinet showing the refrigerating element in elevation;

Fig. 3 is a section of a refrigerating element on the line 3—3 of Fig. 4;

30 Fig. 4 is a bottom plan view of the refrigerating element; and

Fig. 5 is a perspective view of a refrigerating element.

35 Evaporators for the dual purpose of chilling circulating air to cool a refrigerating cabinet and for freezing ice for table use have heretofore been constructed in accordance with the application of Jesse G. King, Serial No. 666,257, filed October 3, 1923, and usually include a header which forms a reservoir for liquid refrigerant, and a number of loops of tubing depending from the header for circulating refrigerant. These loops are arranged to enclose a freezing space, in which are placed shallow pans for freezing ice for table use, and also extend outwardly beyond the freezing space to chill circulating air for cooling the cabinet. The freezing space has been comparatively sheltered from circulating air, one set of tubes being provided principally for ice freezing, and another set for the principal purpose of cooling the circulating air. These evaporators have usually been placed in a corner of the cabinet and leave an

L-shaped storage compartment for food as 55 shown in the application of Harry B. Hull, Serial No. 642,369, filed May 30, 1923. While this arrangement is very effective, the refrigerating element occupies a rather large amount of space. In the case of small cabinets, for instance for apartment house use, the provision of considerable space for food storage is very important. This reduces to a small amount the space available for the refrigerating element in the cabinet. If refrigerating elements of the form previously described are used the legs of the L-shaped storage compartment may be so narrow or short as to be practically useless. Moreover, 60 much space is required where one set of tubes 65 is devoted to freezing ice and another set to the cooling of circulating air. In accordance with my invention I provide an evaporator which is very compact and flat, and which may be disposed entirely across the top of a 70 cabinet thus leaving a substantially cubical space for the storage of food. I also construct the evaporator so that the ice freezing and air cooling elements are combined and 75 space is thus conserved.

80 Referring to the drawings, particularly Figs. 3 and 5, my evaporator includes an elongated and preferably cylindrical horizontal header 10 which forms a reservoir for liquid refrigerant, and conduit means for circulating refrigerant which extends laterally beside the header. The conduit means includes a single tube 11 which is connected at both ends 12 and 13 to the header below the level of the liquid. The tubing is formed, on each side of the header, into a pair of flat, substantially horizontal coils 14, 14' and 15, 15'. Preferably the tube is connected to the header approximately at its center by a conduit 16. The tube 11 may be in a single integral piece, 85 with the conduit 16 connected between it and the header, or as shown in the drawing, the conduit 11 may be formed of two separate pieces which are integrally united by being soldered in openings 17 formed in the side of conduit 16. The end of the conduit 16 may be conveniently closed by a plug 18. The loops or coils 14 and 14' are vertically spaced to permit the insertion between them of a compartment 20 for an ice-making container 90 100 105 21. The compartment is supported on the loop 14' and is thermally connected to both loops 14 and 14' by soldering. Similarly the

loops 15 and 15' are spaced to receive another compartment 20 for another ice-making container.

The evaporator is supported in the top of 5 the cabinet in any suitable manner (as by bolts 22 attached to the top wall of the cabinet) and is placed as near to the top wall as frosting conditions will permit. It will be understood that during operation the evaporator becomes coated with frost, and sufficient space must be left around the evaporator for this frost to form without touching the walls of the cabinet, for if it were permitted to touch the walls, this would increase 10 the heat leakage into the cabinet and also cause the walls to sweat. Accordingly a space 25 indicated in Fig. 2 is left between the header and the top of the cabinet.

Surrounding the evaporator within the 20 cabinet is a U-shaped partition 30 which separates the cabinet into a cooling compartment 31 and a storage compartment 32. This partition extends substantially across the entire width of the cabinet leaving only air circulating flues 33 on either side. The partition is provided at or near its upper ends with openings 34 which admit warm air from the cabinet to the cooling compartment and has an opening 35 admitting cold air from the cooling compartment to the storage compartment. 25 Preferably the bottom wall of the partition is provided with a drip pan 36 and a baffle 37 for the opening, the drip pan being separated from the partition by an insulating air space 38 as more fully described in the application of George F. Hofferberth, filed February 28, 1927, Serial No. 171,437. The front of the cooling compartment is preferably closed by a wall 39 which has openings to admit the ice-making containers 21.

The air circulates as shown by the arrows in Fig. 2, upwardly through the flues 33 and downwardly over the enclosures for the ice-making containers, thence under the coils 45 14' and 15' and out through the opening 35. In this manner the coils serve two purposes, namely, cooling the compartments for the ice-making receptacles and cooling the circulating air which flows under and in contact with them. It will be noted, however, that the compartments themselves form large surfaces projecting into the path of the circulating air. Consequently these compartments also serve to cool the circulating air.

It will be observed that the evaporator 55 above described effectively cools circulating air and that it is provided with considerable ice capacity. Nevertheless the entire evaporator may be contained within a small height 60 and consequently may be installed in a thin space. This is a decided advantage in the case of small cabinets as it increases the space available for the storage of food and permits the construction of a food compartment of a 65 convenient and economical shape.

While the form of embodiment of the invention as herein disclosed, constitutes a preferred form, it is to be understood that other forms might be adopted, all coming within the scope of the claims which follow. 70

What is claimed is as follows:

1. A refrigerating element for refrigerating apparatus including a horizontal header forming a reservoir for liquid refrigerant, conduit means for circulating refrigerant 75 connected to the header and including a pair of spaced substantially horizontal coils extending laterally from the header, and a compartment for an ice-making container disposed between the coils and thermally connected to both of the coils. 80

2. A refrigerating element for refrigerating apparatus including a header forming a reservoir for liquid refrigerant, conduit means extending laterally from the header 85 and including a pair of spaced substantially horizontal coils on each side of the header, and compartments for ice-making containers, one compartment being disposed between the coils of each pair and thermally connected to 90 both coils of the pair.

3: A refrigerating element for refrigerating apparatus including a header for liquid refrigerant, a continuous tube connected at its ends to the header and formed into two pairs 95 of spaced substantially horizontal coils, one pair being disposed on each side of the header, and a connection from the tube to the header between the pairs.

4. A refrigerating element for refrigerating apparatus including a header forming a reservoir for liquid refrigerant, a single tube connected at both ends to the header below the liquid level thereof, the tube being formed into two pairs of spaced substantially horizontal coils, one pair being disposed on each side of the header, and a compartment for an ice-making container supported between and thermally connected to both coils of each pair. 100

5. Refrigerating apparatus comprising in combination a cabinet; a partition dividing the cabinet into a storage compartment and a cooling compartment which occupies substantially the entire width of the cabinet, and providing passages for the circulation of air 110 between the compartments; and a shallow flat refrigerating element extending substantially the entire width of the cooling compartment and including a header, conduit means for circulating refrigerant connected 115 to the header and formed into a pair of spaced substantially horizontal coils on either side of the header, and a compartment for an ice-making receptacle supported between and thermally connected to each of the coils of 120 each pair, said coils and compartments projecting into the path of air circulating through the cooling compartment. 125

6. A refrigerating element for refrigerating apparatus including a header for liquid 130

refrigerant and a continuous tube connected at its ends to the header and formed into two pairs of spaced substantially horizontal coils, one pair being disposed on each side of the header.

7. A refrigerating element for refrigerating apparatus comprising in combination a header, a conduit loop for circulating refrigerant extending laterally from the header

and forming an enclosure for an ice-making container, said loop including a pair of vertically spaced substantially horizontal ducts, and a compartment for an ice-making container disposed within the enclosure and thermally connected to both of the ducts.

In testimony whereof I hereto affix my signature.

OTTO M. SUMMERS.
